UNITED STATES PATENT OFFICE.

CHAUNCEY O. LYMAN, OF BROCKWAYVILLE, PENNSYLVANIA, ASSIGNOR
OF TWO-THIRDS TO ROBERT A. HAMILTON AND WILLIAM T. BLOSE,
OF BIGRUN, PENNSYLVANIA.

SWING.

SPECIFICATION forming part of Letters Patent No. 732,307, dated June 30, 1903.

Application filed November 25, 1902. Serial No. 132,793. (No model.)

To all whom it may concern:

Be it known that I, CHAUNCEY O. LYMAN, a citizen of the United States, residing at Brockwayville, in the county of Jefferson,

5 State of Pennsylvania, have invented certain new and useful Improvements in Swings; and I do hereby declare the following to be a full, clear, and exact description of the invention, such as will enable others skilled in the art to

10 which it appertains to make and use the same.

This invention relates to the class of lawn-swings, and it has for its object to provide a construction wherein two seats are hung in a supporting-frame and which seats and frame

15 with its hangers may be folded into small compass for shipment, so that they may receive a minimum freight-rate.

A further object of the invention is to provide a construction which will be cheap and

20 easy of manufacture and which will be efficient in operation.

Other objects and advantages of the invention will be understood from the following description.

25 In the drawings forming a portion of this specification, and in which like numerals of reference indicate similar parts in the several views, Figure 1 is a perspective view of the swing, showing it set up and ready for use.

30 Fig. 2 is a perspective view showing the platform removed and the several members partly folded. Fig. 3 is a vertical sectional view through a pair of hangers and the adjacent ends of the platform-sills and showing the arrangement of the bushings. Fig. 4 is a detail elevation of one end of a platform-sill and showing a bushing and the manner of holding it in place.

Referring now to the drawings, there is

40 shown a swing, including a supporting-frame, comprising two pairs of uprights 5 and 6. Each of the uprights has a plate 7 secured

against its inner face at its upper end, the plates of the uprights 5 overlapping the plates

45 of the uprights 6, and through the overlapping plates are formed alining perforations, with which is engaged a rod 8, having a head at one end and a nut at the other for preventing disengagement thereof.

50 Bolted at one end against the inner faces of

the uprights 6 are cross-pieces 9 by means of bolts 10, and pivotally secured to the inner faces of the uprights 5, by means of bolts 12, are plates 13, which are in turn pivotally connected to the cross-pieces at their ends by 55 means of the bolts 14, thus forming knee-braces which, when broken, will permit of the uprights being folded together. To hold the knee-braces at times active, the pieces 9 and their corresponding plates 13 are perforated 60 to receive additional bolts 15, so that when said bolts 15 are engaged the plates and cross-pieces are held from displacement either toward or away from each other. The bolts 10 are also engaged through posts 16 and the 65 bolts 12 are engaged through posts 17, so that they may have pivotal movement, said posts being arranged to normally diverge upwardly. A slotted tie-rod 18 is provided for each of the posts, each of said tie-rods being pivotally connected at its upper end with the upper end of a corresponding upright by means of a bolt 19, while through the longitudinally-extending slots of the rods at each side of the frame is engaged a bolt-rod 20, which passes 70 also through the upper ends of a pair of hangers 21 at that side of the frame. By slotting the tie-rods the posts are permitted to be swung with their outer ends upwardly to fold between the uprights 5 and 6, respectively, 75 when the structure is folded for shipment, as hereinafter described and as illustrated in Fig. 2 of the drawings. Through the lower ends of the hangers are formed perforations in which are disposed bushings, the extremities of the hangers being slotted, so that the 80 perforations may be reduced in diameter to grip the bushings, this action being accomplished by means of the bolts 22, which are engaged through the hangers below the perforations.

85 A platform is provided and comprises sills 23, having perforations in their end portions and slots leading outwardly therefrom, and in the perforations are engaged bushings 24, 90 held in place at times by means of the clamping-bolts 25, which are engaged through the sills, as illustrated. By removing the bolts 25 the sills may be moved laterally or the bushings otherwise removed therefrom, when the 95 100

sills may be disengaged from the bolt-rods 26, which are passed through the bushings of the hangers and sills at each end of the platform by reason of the fact that the slots in 5 the ends of the sills are of sufficient widths to permit of the rods being drawn therethrough. Upon the middle portions of the upper faces of the sills is secured a platform comprising transverse slats 27, and pivoted 10 against the outer faces of the sills directly adjacent to the platform are the front legs 28 of seats. The seats comprise side pieces 29, which are pivotally connected by means of bolts with the upper ends of the legs 28 and 15 are also pivotally connected by means of bolts with their respective hangers. The pivot-bolts in question are engaged through bushings which are disposed in perforations in the several members, the members being slotted 20 longitudinally from the perforations and having clamping-bolts engaged therethrough, so that the perforations may be contracted to clamp the bushings, as will be understood. The side pieces 29 of the seats are provided 25 with transverse slats 31. Each seat has a back consisting of two uprights 32, which are pivoted at their lower ends against the inner faces of the side pieces and are connected by transverse pieces 33, to which are attached 30 longitudinal slats 34. Arms 34' are pivoted at their rear ends to the uprights 32 and have depending webs 35, to which are bolted supports 36, by means of two bolts 37 and 38, the lower ends of the supports being connected 35 to the forward portions of the side pieces of the chairs by single bolts 39, as shown. Thus when the lower bolt 38, which connects the web of each arm with its support, is withdrawn the back may be folded forwardly upon 40 the seat, and when the bolts at the lower ends of the front legs are withdrawn the seat and back may be raised and folded between the hangers. Thus it will be seen that by removing one bolt from each of the knee-braces, the 45 four bolts from the lower ends of the front legs of the chairs, and four bolts from the arm-supports and removing the platform the uprights 5 and 6 may be brought together and all of the working parts may be folded there- 50 between, the platform being laid also between the uprights. The entire structure may therefore be folded into an extremely small space for shipment, while the structure itself is such that it may be made at a small cost and 55 will be most durable.

It will be understood that in practice modifications of the specific construction shown may be made and that any suitable materials and proportions may be used for the various parts without departing from the spirit of the 60 invention.

What is claimed is—

1. A swing comprising convergent pairs of uprights having a hinge connection at their upper ends, upwardly-divergent pairs of posts pivoted to the uprights, slotted tie-rods pivotally connected at the upper ends of the uprights, bolts engaged with the upper ends of the posts and with the slots of the tie-rods, hangers pivoted upon the bolts and chairs 65 carried by the hangers.
2. A swing comprising convergent pairs of uprights having hinge connections at their upper ends, upwardly-projecting posts pivoted at their lower ends to the uprights, tie-rods pivotally connected at their upper ends with the uprights and with which the upper ends of the posts are slidably connected whereby the posts and tie-rods may be folded against their respective uprights, hangers 75 connected with the upper ends of the posts, and chairs carried by the hangers.
3. A swing comprising uprights having hinge connections at their upper ends, knee-braces connecting the uprights, means for 80 holding the knee-braces rigid at times, posts pivoted to the uprights at the ends of the knee-braces, tie-rods pivotally connected with the upper ends of the uprights and with which the posts are slidably connected, and seats 85 suspended from the posts.
4. A swing comprising a supporting-frame including pivoted members adapted to fold together, hangers swung from the frame, a platform removably connected with the hangers, a chair-seat pivoted to the hangers and having front legs pivoted thereto and to the platform, said legs being removable from the platform, a back comprising uprights pivoted to the seat, arms pivoted to the uprights and having depending webs, and supports pivoted to the seat and webs and having means for holding them at times against pivotal movement with respect to the web. 90

In testimony whereof I affix my signature 105 in presence of two witnesses.

CHAUNCEY O. LYMAN.
